UNITED STATES PATENT OFFICE.

HARRY N. GREEN, OF HAGERSTOWN, MARYLAND.

AUTOMATIC TIME DISPLAY MACHINE.

Application filed May 4, 1922. Serial No. 558,550.

To all whom it may concern:

Be it known that I, HARRY N. GREEN, a citizen of the United States, residing at Hagerstown, Washington County, Maryland, have invented a new and useful Automatic Time Display Machine, of which the following is a specification.

This invention relates to display devices, and has special reference to a card or sign displaying device.

More particularly, the invention relates to that class of devices wherein a number of cards or signs are arranged on an endless belt within the casing, the signs being brought successively before a sight opening.

One important object of the invention is to provide an improved general construction of devices of this character.

20 A second important object of the invention is to provide a sign displaying device of this character wherein the movement of the card belt will be intermittent, and wherein a suitable shutter will be interposed between the sight opening and the card belt during the period of such movement.

A third important object of the invention is the provision, in a device of this sort, of a pair of endless belts, one of which carries or consists of the cards or signs to be displayed, while the other is provided with alternate shutter and sight spaces, said belts being operated in timed relation.

35 A fourth important object of the invention is the provision, in a sign displaying device of this character, of novel means for operating the belts of the device in timed relation.

With the above and other objects in view 40 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a side elevation partly in section 50 taken from one side of the device.

Fig. 2 is a similar view taken from the opposite side thereof.

Fig. 3 is a front elevation of the device partly in section.

Fig. 4 is a detail view of a portion of one of the sign carrying belts. 55

Fig. 5 is a similar view to Fig. 4, but showing a portion of the shutter belt.

Fig. 6 is a detail end view of one of the clamps employed therein. 60

Fig. 7 is an enlarged detail view of a portion of one of such clamps taken from the side thereof.

Fig. 8 is a detail plan view of the driving mechanism used herewith for causing proper timed movement of the belts. 65

Fig. 9 is a front view of such driving mechanism partly in section.

Fig. 10 is an end view of the driving mechanism. 70

Fig. 11 is a detail of such driving mechanism showing the sprocket chain and sprockets in side elevation.

Fig. 12 is a detail edge view of one of the tripping disks. 75

Fig. 13 is a detail edge view of the other tripping disk.

In carrying out the objects of the invention, there is provided a casing 10, having at its front and back suitable window openings, preferably glass 11. These window openings constitute front and rear sight openings. In the upper part of the casing, there is journaled a pair of shafts 12, whereon are pulleys 13, over which run the chains 14 which form the sign carrying belts, and which are connected by clamping devices 15, each of which consists of a rigid back member 16 having a bar 17 extending from end to end thereof, said bar being supported in suitable lugs 18. Surrounding the bar 17 are coil springs 19 having terminal ends 20 which press down on the back 16, and thus serve, when a card or the like is inserted between them and said back, to hold the card in position. The chains 14 run also over sprockets 21, which are carried on shafts 22, extending through the sides of the casing and being provided on one end with sprockets 23. Extending through the sides of the casing adjacent the bottom is a shaft 24, this shaft being formed in two sections, and carrying on one section a sprocket 25. Around the sprocket 25 and the sprocket 23 passes a driving chain 26. Similarly there is provided in the top of the casing a pair of shafts 27, which carry sprockets 28, and adjacent the shafts 80

22 are shafts 29 carrying sprockets 30. Around the sprockets 28 and 30 extend chains 31, provided with clamps 32, similar to the clamps 15. These chains 31 constitute the shutter carrying chains, and suitable blank cards, which may be black, white or colored, are held at intervals of the chains 31 by the clamps 32. The ends of the shafts 29 project through one side of the casing, 10 and on these projecting ends are sprockets 33. The remaining section of the shaft 24 projects through this end of the casing, and carries a sprocket 34. Around the sprockets 33 and 34 extends the driving chain 35. 15 Suitable mechanism, presently to be described, is provided which is so arranged that the belts 14 and 31 are moved in timed relation. It is preferred that the belt 31 have four sections, two of said sections being open or transparent, while the other two are opaque. In the operation of the device, a card to be displayed may be seen through the glazed window 11 at the time when the two open or transparent sections 25 of the belt 31, on this side of the apparatus, are opposite each other. Prior to the movement of the belt 14 for the display of the next card, the timer mechanism actuates the belt 31 until the two opaque sections of this 30 belt are brought between the card and the glazed window 11. As soon as this takes place, the belt 31 ceases to move, and the belt 14 will then move sufficiently to bring the next succeeding card opposite the window 11, and will then come to rest. As soon as the belt 14 comes to rest, the belt 31 again moves to bring the two open or transparent portions opposite the window 11, so that the new card can be observed. 35 40 Considering now the mechanism by which this is accomplished:

Within the casing 10, there is provided a base 36, extending up from which are standards 37, carrying the sections of the shaft 24, the same being in the form of sleeves. Through the sleeves passes a rod or shaft 38, and on this rod or shaft between the inner ends of the sleeves is mounted a sprocket wheel 39, which is connected by a chain 40 with a sprocket 41, mounted on a shaft 53, supported in bearings 43 carried by the base 36. The shaft 42 is provided with a gear 44 wherewith meshes a pinion 45, carried by a motor 46 on the shaft. The sprocket 39 is provided with a boss 47 on each side, and from each of these bosses projects a radial finger 48. Splined slidably on each section 24 of the shaft is a clutch member 49, having a laterally projecting finger 50, which is engaged by the finger 48 whenever the clutch member 49 is forced to its innermost position by the spring 51, which surrounds the respective shaft section 24, and bears against one 55 of the standards or bearings 37. Thus,

whenever the clutch member 49 is forced inward, the shaft section 24 will revolve therewith, and consequently, as previously described, the belts which are driven by that shaft section will move. 70

On the shaft 53 is a gear 51', which meshes with a pinion 52 on the shaft 42 supported in the rear bearing standards 43. On this shaft 42 is a crank disk 54 provided with a crank pin 55 whereto is connected one end of a pawl 56, which has its free end extending forwardly and urged upwardly by a spring 57. This free end engages a ratchet 58 fixed on a shaft 59 supported in bearings 60. On the shaft 59 is mounted a pair of worms 61, each of which meshes with a horizontal worm wheel 62, one of these worms 61 is fixed to the shaft 59, while the other worm 61 is provided with a hub 63, having a series of peripheral notches 64, engageable by a finger 65 pivotally mounted on a sleeve 66 fixed to said shaft 59. Thus this worm wheel 62 may be rotated with respect to the shaft 59, and locked in such rotating position by the engagement of the finger 65 in a respective notch 64. Each of the clutch members 49 is provided with a spirally extending peripheral groove 67, and adjacent each of these members there is mounted a lever 68, having a downwardly extending finger 69 adapted to enter the respective groove 67 when this end of the finger is depressed. The other end of this lever 68 terminates in a tail 70, which lies beneath the respective worm wheel 62, and on the worm wheel which controls the card belt, there is provided a single tripping cam 71, while the other worm wheel is provided with a pair of tripping cams 72, similar to the cam 71. The position of these cams on the wheels is regulated by providing the peripheral portions of said wheels with a series of openings 73 wherein the stems 74 of these cams may fit. 95 100 105

In the operation of this part of the device, it will be noted that the fingers 69 are normally engaged in the groove 67, so that the clutch members 49 are drawn back and held back. As the motor operates, the ratchet 58 will be rotated, and this will drive the shaft 59, which in turn operates the worm wheel 62. Assuming that the transparent or open portions of the outer belts are opposite the windows, and a card displayed, the effect will be as follows: 110 115 120

The worm wheel 62 will rotate until the first of the tripping cams 72 contacts with the tail 70 of the respective lever 68. This will move the finger 69 of that lever out of its groove 67, and the spring 51 will force the clutch member 49 inward. This causes the revolution of one section 24 of the shaft, and the belt 31 will be driven to bring the opaque portions opposite the window on each side of the device. As the tail 70 slips 125 130

off of the first tripping cam 72, the tail 70 of the other lever 68 is engaged by the tripping cam 71 with the result that the other clutch member is released. Also as the 5 tail of the first lever slips off, the finger 69 engages in its groove 67 and draws the first clutch member out of engagement so that the outer belts cease to move, while the inner or card belts now move. The card belts 10 complete their movement at the time when the cam 71 passes from beneath the tail of its lever 68, whereupon the second tripping cam 72 engages the tail of the first lever 68, and the outer belts are again moved. Thus 15 it will be seen that the mechanism just described first, effects closing of the windows 11, second, movement of the inner belts, and third, opening of the windows 11.

There has thus been provided a simple 20 and efficient device of the kind described and for the purpose specified.

It is obvious that minor changes may be made in the form and construction of the invention without departing from the material spirit thereof. It is not, therefore, 25 desired to confine the invention to the exact form herein shown and described, but it is desired to include all such as properly come within the scope claimed.

30 Having thus described the invention, what is claimed as new, is:—

1. In a display device, an endless card carrying belt, an endless shutter carrying belt supported wholly in front of the card carrying belt and having spaced shutters thereon positioned to cross each other during closing movement, and means for intermittently moving said belts, said means being arranged to move in succession the shutter belt from open to closed position, the card belt, and the shutter belt from closed to open position.

2. In a display device, a card carrier arranged to display a succession of cards, a 45 shutter device including an endless belt supported wholly in front of the card carrier and having spaced shutters thereon positioned to cross each other during closing movement of the shutter device, and driving means for said carrier and shutter device, said driving means being arranged to intermittently move the carrier to bring successive cards into display position and permit them to rest in such position, said 55 driving means being further arranged to intermittently move the shutter device to close off the cards during the movement of the card carrier.

3. In a display device, a card carrier, a

shutter device, a shaft for actuating the 60 card carrier and having operative connection therewith, a second shaft for actuating the shutter device and having operative connection therewith, a driving wheel, clutches for connecting said shafts to said driving 65 wheel, and means for clutching and unclutching the clutches in timed relation.

4. In a display device, a card carrier, a 70 shutter device, a shaft for actuating the card carrier and having operative connection therewith, a second shaft for actuating the shutter device and having operative connection therewith, a driving wheel, clutches for connecting said shafts to said driving 75 wheel, springs urging said clutches into clutching position, means for drawing said clutches out of clutching position and holding them withdrawn, and a trip device for disengaging said means from the clutches in 80 timed relation.

5. In a display device, a card carrier, a 85 shutter device, a shaft for actuating the card carrier and having operative connection therewith, a second shaft for actuating the shutter device and having operative connection therewith, a driving wheel, clutches for connecting said shafts to said driving 90 wheel, springs urging said clutches into clutching position, said clutches each having a spiral groove in its periphery, fingers 95 normally engaging said grooves and movable laterally with respect to the clutches to enter and leave said grooves, said fingers when in said grooves effecting withdrawal of said clutches, and means to move the 95 fingers into and out of said grooves in timed relation.

6. In a display device, a card carrier, a 100 shutter device, a shaft for actuating the card carrier and having operative connection therewith, a second shaft for actuating the shutter device and having operative connection therewith, a driving wheel, clutches for connecting said shafts to said driving 105 wheel, springs urging said clutches into clutching position, said clutches each having a spiral groove in its periphery, fingers normally engaging said grooves and movable laterally with respect to the clutches to enter and leave said grooves, said fingers 110 when in said grooves effecting withdrawal of said clutches, a motor for driving said wheel, timer cam wheels arranged to effect temporary withdrawal of said fingers from said grooves in timed relation, and an operative connection between the motor and timer wheels.

HARRY N. GREEN.
